REGISTER MECHANISM

Anna L. Hathaway, Melrose, William A. Waterman, Cambridge, and John W. Burgess, Wakefield, Mass.

Application April 18, 1940, Serial No. 330,342

5 Claims. (Cl. 235—114)

This invention relates to improvements in manually operated golf stroke registers, adapted to be carried by a player and to be operated by him to register the number of strokes made in progressing from one hole to the next and also registering the total number of strokes made in traversing the entire course.

The object of the invention is to simplify and improve registers of the class indicated, and to this end we have provided an improved register having the features of construction and operation set forth in the following description, the several novel features of the invention being pointed out and defined in the claims at the close of the description.

In the accompanying drawings:

Figure 1 is a top plan view of our improved register.

Figure 2 is a side view of the register shown in Fig. 1 with the outside casing shown in section on line 2—2 and the inside mechanism shown in section on line 2—3 of Fig. 1.

Figure 3 is a top plan view of the inner casing or frame hereinafter described.

Figure 4 shows the inner casing with its top plate removed.

Figure 5 is a section on line 5—5 of Fig. 4, but showing the top plate in position and some of the parts of Fig. 4 removed.

Figure 6 is a view similar to Fig. 4, but with the hole-to-hole counting wheel, hereinafter described, removed.

Figure 7 is a view similar to Fig. 6, but with the actuating push-bar and partition, hereinafter described, removed.

Figure 8 is a section on line 8—8 of Fig. 6.

Figure 9 illustrates a detail of the inner casing.

As shown in Figs. 1 and 2, the illustrated embodiment of this invention comprises an outer casing consisting of two cup-shaped sheet metal sections 10 and 11 telescopically fitted together and held against separation by friction or any other suitable means. This outer casing provides a housing for the registering mechanism which includes an inner casing or frame comprising a cup-shaped body 12 to which a top wall 13 (Figs. 2 and 3) is fastened by means of screws 14. The top wall 13 is made adjacent to one end thereof with a window opening 15 which is in register with a window opening 16 provided in the section 11 of the outer casing, and adjacent its opposite end the top wall 13 is made with a window opening 17 that is in register with a window opening 18 formed in the upper section 11 of the outer casing. The openings 15 and 16 expose

to view the top marginal portions of two disk counting wheels 19 and 20 (Figs. 2 and 7), the former bearing upon its top side two series of numerals from 0 to 9 and the latter bearing upon its top marginal portion a series of numbers from 0 to 19. The openings or windows 17 and 18 expose to view the top marginal portion of a disk counting wheel 21 (Figs. 2 and 4) which bears upon its top side a series of numerals from 0 to 19.

The counting wheel 21 is provided upon an arbor 22 (Figs. 4 and 5) whose upper end is journaled in a bearing provided by top wall 13 of the inner frame or casing, while the lower end of arbor 22 is journaled in a bearing provided in a partition wall 23 that is fastened in position within the body 12 of the inner frame or casing by means of screws, or otherwise.

The counting wheel 20 is fixed on an arbor 24 (Figs. 7 and 8) whose lower end portion extends loosely through a hole provided in the bottom wall of body 12 of the inner frame or casing and loosely through a hole formed in the bottom wall of the section 10 of the outer casing to the exterior of the latter where it has fixed on it a thumb wheel or the like 25 (Fig. 2). The counting wheel 19 is journaled loosely upon the upper end portion of spindle 24. The upper portion of spindle 24 extends loosely through an aperture provided through a thin sheet metal bracket 26 (Figs. 7 and 8) forming a rigid part of the body 12 of the inner frame or casing. This bracket separates the two wheels 19 and 20 and also affords lateral support for the upper end portion of spindle 24.

Occupying a position alongside of partition 23 is a push-bar 27 (Figs. 2, 4 and 6) formed adjacent to one end thereof with a longitudinal slot 28 that is occupied by a screw 29 projecting upwardly from a bracket 30 forming part of the body 12 of the inner frame or casing. The opposite end portion of push-bar 27 extends through registering notches provided in the flanges of body member 12 and of the two sections of the outer casing to the exterior of the latter, as shown in Figs. 1 and 2, the outer end portion of said push-bar being adapted to be engaged by the finger of the operator. A spring 31 (Figs. 2, 4 and 6) yieldingly holds the push-bar 27 normally at the limit of its outward movement where it abuts the interior of the body 12 of the inner frame or casing.

As shown in Fig. 6, push-bar 27 carries upon its top side three spring push pawls 32, 33 and 34, the pawls 32 and 33 cooperating, respectively,

with the counting wheels 20 and 19, while the pawl 34 cooperates with the counting wheel 21.

Counting wheel 21 is made with a circular series of holes 35 which provides a circular series of abutment shoulders to be engaged by the spring pawl 34 which curves upwardly from push-bar 27 into position against the bottom side of wheel 21 with its nose in position to engage the holes 35 (Fig. 2). That is to say, the spring pawl 34 is bent upwardly from push-bar 27 so that it bears against the bottom side of counting wheel 21.

The spring pawl 33 is bent downwardly into an aperture 37 (Fig. 6) formed through push-bar 27 and yieldingly rests against the top of counting wheel 19 with its nose in position to cooperate with a circular series of holes 38 formed through said counting wheel 19.

Disposed radially outside of the circular series of holes 38 are two apertures 39, said two apertures being disposed diametrically opposite each other with one of said apertures disposed immediately in front of the nose of the spring pawl 32 when either one of the two numerals "9" on wheel 19 is exposed at the window openings 15—16 and at a window 15a formed through the partition 23. The three windows 15, 15a and 16 are in alinement and through them can be seen the numbered marginal portions of counting wheels 19 and 20, as shown in Figs. 1, 3 and 6.

Inward movement of push-bar 27 is limited by the engagement of its inner end with the adjacent end wall of the inner frame or casing 12 and when said push-bar is shoved inwardly by finger pressure it acts through spring pawl 34 (Figs. 2 and 4) to move counting wheel 21 one step and simultaneously acts through spring pawl 33 to move counting wheel 19 one step. When one of the apertures 39 occupies a position directly and immediately in front of the nose of spring pawl 32, as shown in Fig. 6, and push-bar 27 is shoved inwardly, the nose of pawl 32 passes downwardly through said aperture 39 and through a slot 36 (Fig. 9) formed in bracket 26 and engages one of a circular series of holes 40 (Fig. 7) formed in counting wheel 20, thereby advancing counting wheel 20 one step as counting wheel 19 is moved forward one step by pawl 33.

At the same moment that counting wheels 19 and 20 are simultaneously advanced one step by the pawls 32 and 33 the pawl 34 (Figs. 2, 3, 4 and 6) will also act to advance counting wheel 21 one step, but this simultaneous operation of all three wheels occurs only twice during each revolution of wheel 19 when a numeral "9" is moved away from windows 15, 15a and 16. At all other times the two wheels 19 and 21 are simultaneously advanced one step for each inward movement of push-bar 27.

The counting wheel 21 (Figs. 2, 4 and 5) has compounded with it a pinion 41 which is in mesh with a pinion 42 provided at the inner end of a stem 43. This stem 43 is journaled in a hole provided in the top wall 11 of the outer casing and at its outer end it is provided with a finger wheel 44 for use in resetting wheel 21 back to zero position. The finger wheel 25 (Fig. 2) which is connected with counting wheel 20 is for use in resetting the latter back to zero.

In using our improved register the operator actuates push-bar 27 each time he makes a stroke while travelling from one hole to the next and when he arrives at the latter there is exposed at the windows 17—18 a number corre-

sponding with the number of strokes made in travelling between the two holes. Then, by means of the finger piece 44 which he rotates in a right hand direction, he sets wheel 21 forward to zero before starting for the next hole.

After traversing the entire golf course the total number of strokes made by the player is registered at the windows 15, 15a and 16, and after making a registration of this number the operator resets wheels 19 and 20 to zero. This is accomplished by operating push-bar 27 until zero on wheel 19 shows at the window; then resetting wheel 20 to zero by using the finger-piece 25, and then using the finger-piece 44 to reset wheel 21 to zero.

The section 10 of the outer casing may be provided at its opposite ends with eyes 45 for the attachment thereto of suitable straps 46 for use in fastening the register to a player's wrist; or any other suitable means may be provided upon the outer casing for attaching the device to any suitable support where it is conveniently accessible for operation either by the player or by an attendant.

A detent 47 fastened to the top plate 13 (Fig. 3) extends downwardly through an aperture 48 provided through said plate and engages the holes 35 of wheel 21 to prevent reverse movement of the latter. A spring detent 49 (Fig. 6) cooperates with the holes 38 of wheel 19 to prevent reverse movement of the latter, said detent being fastened within a recess (not shown) provided upon the bottom side of partition 23.

A spring detent 50 (Figs. 6 and 8) is fastened in position upon the bottom side of body 12 and its free end extends upwardly through a hole 51 to cooperate with the series of holes 40 so as to hold wheel 20 against reverse movement.

The above described register mechanism is of simple, compact, inexpensive and efficient construction comprising a single actuator 27 for three counting wheels and so organized and arranged that upon arrival of the golf player at each hole the wheel 21 can be independently adjusted so as to set it at zero before starting toward the next hole and this resetting is accomplished without disturbing the total strokes indicating wheels 19 and 20 which are in reset to zero until the arrival of the player at the end of the course.

What we claim is:

1. A registering device for use by golf players, said device having, in combination, a housing; a numbered counting wheel rotatably supported within said housing and operable to register the number of strokes made by the player in travelling from one hole of the course to the next hole; a pair of numbered counting wheels rotatably supported within said housing and cooperatively associated to jointly register the total number of strokes made by the player in traversing the entire course; a single-wheel-actuating member mounted for reciprocatory movement within said housing and having one end thereof extending to the exterior of the latter so that it is accessible for manual operation of said member; a spring normally holding said member at the limit of its movement in one direction; a pawl on said member operable to rotatively adjust said first-mentioned wheel one step each time said member is manually operated; a second pawl on said member operable to rotatively adjust one of the wheels of said pair one step each time said member is manually operated, and a third pawl on said member operable to rotatively adjust the

other wheel of said pair one step simultaneously with each tenth manual operation of said member.

2. A registering device of the character described constructed in accordance with claim 1 and wherein the engagement of said third pawl with its wheel of said pair is controlled by the other wheel of said pair.

3. A registering device of the character described constructed in accordance with claim 1 and wherein the wheel of said second pawl normally holds said third pawl out of engagement with its wheel and is made with an aperture through which said third pawl has access to its wheel to advance the latter one step during each tenth operation of said member.

4. A registering device for use by golf players, said device having, in combination, a housing; a numbered counting wheel in the form of a disk rotatably supported within said housing and operable to register the number of strokes made by the player in travelling from one hole of the course to the next, said disk wheel being formed with a circular series of apertures, one for each number; a pair of numbered counting wheels in the form of disks rotatably supported within said housing in parallelism one above the other and cooperatively associated to jointly register the total number of strokes made by the player in traversing the entire course, each disk wheel of said pair being formed with a circular series of apertures, one for each number of said disk wheel, and the uppermost wheel of said pair being of smaller diameter than the lowermost wheel of said pair; a single wheel-actuating member mounted for reciprocatory movement within said housing and having one end thereof extending to the exterior of the latter so that it

is accessible for manual operation of said member; a spring normally holding said member at the limit of its movement in one direction; a pawl on said member to cooperate with the holes of said first-mentioned wheel to move the latter one step each time said member is manually operated; a second pawl on said member cooperating with the holes of the smaller wheel of said pair to rotatably adjust said wheel one step each time said member is manually operated, and a third pawl on said member controlled by said smaller wheel and cooperating with the holes of the larger wheel of said pair to rotatably adjust the latter one step simultaneously with each tenth manual operation of said member.

5. A registering device for use by golf players, said device having, in combination, a housing; a numbered counting wheel rotatably supported within said housing and operable to register the number of strokes made by the player in travelling from one hole of the course to the next hole; a pair of numbered counting wheels rotatably supported within said housing and co-operatively associated to jointly register the total number of strokes made by the player in traversing the entire course; a single wheel-actuating member mounted for reciprocatory movement within said housing and having one end thereof extending to the exterior of the latter so that it is accessible for manual operation of said member, and a spring normally holding said member at the limit of its movement in one direction, said actuating member being provided with means through which it directly actuates each wheel independently.
